FOOD BASTING ATTACHMENT FOR BOTTLES OR THE LIKE

Bathuel Rafael Posada, 3700 Dean Drive, Apt. 1207,
Ventura, Calif. 93003

Original design application Aug. 20, 1968, Ser. No.
13,208. Divided and this application May 8, 1969,
Ser. No. 17,066

Term of patent 14 years

Int. Cl. D9—02

U.S. Cl. D9—275

FIG. 1

FIG. 2

FIG. 3

FIG. 4

FIG. 1 is a perspective view of a food basting attachment for bottles or the like showing my new design;

FIG. 2 is a top plan view;

FIG. 3 is a bottom plan view; and,

FIG. 4 is a side elevational view.

This is a division of design application Ser. No. D. 13,208, filed Aug. 20, 1968, now Pat. No. D. 215,416, granted Sept. 30, 1969.

I claim:

The ornamental design for a food basting attachment for bottles or the like, substantially as shown and described.
